UNITED STATES PATENT OFFICE

EDWARD LAPP, EDWARD A. KRAH, JR., AND ALBERT WOLPERT, OF PITTSBURGH, PENNSYLVANIA, ASSIGNORS TO PITTSBURGH WATER HEATER COMPANY, OF PITTSBURGH, PENNSYLVANIA, A CORPORATION OF NEW JERSEY

GAS FIRED HEATER

Application filed March 22, 1927. Serial No. 177,940.

This invention relates to gas fired heaters, and more particularly to pilot valve devices applicable to such heaters.

One of the primary objects of our invention is to increase the certainty and safety of operation of gas fired heaters.

Another object of the invention is to attain the foregoing by simple and direct-acting means with the least possible complication of apparatus.

More specifically, our invention contemplates the provision of means under the influence of the pilot light of a gas heater to control the admission of gas to the main burner, and we have embodied the invention in preferred form, in a safety pilot valve, operating, when the pilot is burning, to provide an open connection from the usual thermostatically-controlled valve in the gas supply line to the main burner, and when the pilot is not burning or has gone out from any cause whatever, to shut off such connection so that no gas will be delivered to the main burner, even if the thermostat becomes cold and opens the said thermostatically-controlled valve.

The nature, objects and advantages of the invention will, however, appear more clearly from the following description, reference being had to the accompanying drawings, wherein:—

Fig. 1 is an elevational view of a gas water-heating apparatus embodying our invention, a certain portion of the figure being in section; and

Fig. 2 is an enlarged vertical longitudinal sectional view of the safety pilot valve employed in carrying out the invention.

Referring now to Fig. 1, it will be seen that we have therein illustrated a water heater 2, having a shell 3, a water heating coil 4, and a main burner 5, supplied with gas from the pipe or main 6 through the intermediation of certain valves, to be hereinafter described.

A pilot 7, so mounted as to extend into the heater through the shell 3, is supplied with

gas, as from the main 6, through a pipe 8 controlled by a valve 9, and is provided with one or more orifices 10 (see Fig. 2) adapted to project a constant flame in proximity to the main burner 5.

The gas supply to the main burner from the gas pipe 6 is by way of a hand-operated valve 11 (normally open); a controlling valve 12 of any suitable type, for example a thermostatically-operated valve, (such valves, operable upon a drop or rise in the temperature of water in the storage tank 13 below or above a certain predetermined point, respectively, being well known in the art); and from thence through a pipe 14 in which is placed the safety pilot valve device 15 of the present invention (normally held in open position under the influence of the heat from the pilot, by means now to be described).

The pilot valve device 15, which may be mounted on the heater shell 3, by bolts 18, has a valve chamber 16, communicating at top and bottom with the gas line 14 of the burner, and enclosing the valve parts proper, and a second chamber or cavity 17 surrounding the outer portion of the pilot and containing valve-controlling means adapted to be heated thereby. The cavity 17 (as shown in Fig. 2) may be open at the bottom, and communicates near the top through a port 19 into the heater casing to provide a flue above the pilot, which latter is provided with a jet opening 10a outside the heater casing 3. Positioned near the flame from jet 10a is a curved, expandible and contractible, or thermostatic element 20, one end of which is fixed at 21 and the other end of which is attached to or engages the end 22 of a lever 23 pivoted at 24. The other end of lever 23 engages a pin or stem 25 as by means of lock nuts 26, said stem being in two parts, screwed together and clamping the diaphragm 27 between them as shown in Fig. 2.

The mechanism in valve chamber 16 is operated by means of the stem 25 which is

positioned by the diaphragm 27 pinched between the casing of chamber 16 and a cap 28. This construction permits of longitudinal motion of the stem by flexure of the diaphragm, but prevents gas from escaping around the stem. The upper end of stem 25 engages a lever 29, as by means of lock nuts 30, said lever being fulcrumed at one end at 31, and at the other end engaging the action spool 32 of the valve 33, which latter is adapted to seat at 33a. The spool 32, slideable on valve stem 34, bears upon the valve through the intermediation of a positioning spring 35. The stem 34 is positioned by a sleeve-like guide nut 36, having longitudinal openings or grooves 36a providing passage for the gas, and a lock screw 37 in its upper end for adjustment of the nut longitudinally of the valve stem. The valve is of the snap action type, such action being obtained by means of the fixed spring or springs 38 which engage a beveled annular rib 39 on spool 32. The snap action may be accentuated by constructing the lever 29 of a relatively thin strip of spring steel or other suitable resilient material.

It will be obvious that the cap into which the gas inlet pipe 14 is screwed serves to secure the parts inside the casing as well as to give access thereto for inspection, removal or repair.

From the foregoing description it will be clear that in operation the device provides an open connection for the gas to the main burner as long as the pilot remains lit, the heat from the pilot jet 10a maintaining the curved thermostatic element 20 in expansion, thus holding the valve 33 open (as shown in Fig. 2) by means of lever 23, stem 25, lever 29, spool 32 bearing upwards against guide nut 36, and valve stem 34 fixed in said nut. With the safety pilot valve so held open (which is its normal position) gas will flow therethrough from pipe 14 to the main burner 5, whenever thermostat valve 12 is opened by a drop in the temperature of the water in the storage tank 13 below a predetermined point. If, however, the pilot light at any time should go out, expansion element 20, deprived of the heat of jet 10a, will exert a force by contraction which pulls down on stem 25 and thence on lever 29 and spool 32, the rib 39 thereof snapping below the ends of springs 38, and the valve 33 closing under the pressure then put upon spring 35. The length and tension of this spring, with relation to the position of the spool when the rib 39 is below the fixed springs 38, is such that valve 33 is maintained firmly seated at 33a. Relighting of the pilot will, of course, cause a reversal of the foregoing valve action.

It will be seen that by our safety pilot valve device we have provided a positive and direct-acting means under the influence of the heat of the pilot to shut off, by snap ac-

tion, the main gas supply to the burner in case such pilot light fails, that the device is compact, rugged and easily adjusted or repaired, and that new pilot tips or expansion elements may be inserted without any necessity of opening the gas chamber of the valve. 70

What we claim is:—

1. A pilot controlled valve device comprising a thermostatic element positioned within the influence of the pilot light, a gas supply line, a valve in said line, and operating connections between said valve and said element, including an action member resiliently associated with the valve, resilient means for holding said member in either of two positions, and lever means operatively connected between said member and said element to move the member from one position to another upon expansion or contraction of said element. 80

2. A pilot controlled valve device comprising a thermostatic element positioned within the influence of the pilot light, a gas supply line, a valve in said line, and operating connections between said valve and said element, including an action member associated with the valve, resilient means for holding said member in either of two positions, a pivoted lever engaging said element, a resilient lever engaging said member, and an operating connection between the levers. 90

3. In a pilot controlled valve device of the character described, a valve having a stem, a sleeve threaded on the stem for adjustment, a spool slideable on the stem between the sleeve and valve, a pilot, actuating means for sliding the spool, said means being operable by the heat of the pilot, and resilient means engaging the spool yieldingly resisting initial sliding movement thereof. 100

4. In a pilot controlled valve device of the character described, a valve having a stem, a sleeve threaded on the stem for adjustment, a spool slideable on the stem between the sleeve and valve, a pilot, actuating means for sliding the spool, said means being operable by the heat of the pilot, and resilient means engaging the spool yieldingly resisting initial sliding movement thereof, together with a spring interposed between the spool and the valve. 110

5. In a pilot controlled valve device of the character described, a valve having a stem, a sleeve threaded on the stem for adjustment, a spool slideable on the stem between the sleeve and valve, a pilot, actuating means for sliding the spool, including a thermostatic element under the influence of the pilot and adjustable operating connections between said element and said spool, and resilient means engaging the spool yieldingly resisting initial sliding movement thereof. 120

6. In a pilot controlled valve device of the character described, a valve having a stem, a sleeve threaded on the stem for adjustment, 125

a spool slideable on the stem between the sleeve and valve, a pilot, actuating means for sliding the spool, said means being operable by the heat of the pilot, and resilient means 5 engaging the spool yieldingly resisting initial sliding movement thereof but finally accelerating the movement.

In testimony whereof we have hereunto signed our names.
